UNITED STATES PATENT OFFICE.

OTTO EBERT, OF CLEVELAND, OHIO.

CHUCK.

1,067,902.

Specification of Letters Patent. Patented July 22, 1913.

Application filed October 3, 1912. Serial No. 723,746.

To all whom it may concern:

Be it known that I, OTTO EBERT, citizen of the United States, residing at Cleveland, in the county of Cuyahoga and State of Ohio, have invented certain new and useful Improvements in Chucks, of which the following is a specification.

This invention relates to chucks or vises for machine tools, such as planers, millers and other metal working machines, and has for its object to provide improved means for pulling down the work, so as to clamp the same flatly on the base of the chuck.

For the sake of accuracy it is essential that the work be held exactly level or flat against the base. With ordinary chucks efforts are often made to reach this result by hammering the work down, but when this is done it has been found that the work will rebound to a certain extent, or the jaws will spring the work, with objectionable results. By the present invention I employ movable face plates on the jaws, which by means of screws can be forced down to hold the work perfectly against the base.

The invention is illustrated in the accompanying drawings in which—

Figure 1 is a vertical longitudinal section of the chuck. Fig. 2 is a horizontal section. Fig. 3 is a section on the line 3—3 of Fig. 1. Fig. 4 is a back view of one of the jaw plates. Fig. 5 is a section on the line 5—5 of Fig. 1.

Referring specifically to the drawings, 30 indicates the base or bed plate of the chuck, and this is provided with the fixed jaw 8 and the movable jaw 7 operated by a screw 6 with flanges 13 to prevent the travel of the screw. The movable jaw is clamped to adjusted position by bolts 11, the heads of which slide in undercut slots 12 in the bed plate. These parts are not substantially different from known chucks. The flanges 13 bear against a block or lower bearing piece 15, held by an upper bearing piece 14 and 45 bolts 16, the bearing pieces being mortised into the bed plate.

Each jaw 7 and 8 is provided with a movable jaw plate 9, slideable up and down thereon, operated by a screw 10 tapped into the 50 jaw and having a collar 10^a which engages in a groove 20 in the back of the jaw plate. This screw may be operated by a socket

wrench, to raise or lower the jaw plates. The jaw plates are confined and guided on the jaws by means of angular guide pieces 55 17 at opposite sides, said guide pieces being secured to the jaw plates by screws 19 and traveling in guide grooves 18 in the sides of the jaw.

In use, the work is placed between the 60 jaws and clamped by means of the screw 6; then the screws 10 are turned so as to force the jaw plates 9 downwardly until the work held by these plates rests level and solidly on the base. The clamp bolts 11 may be 65 tightened to hold the movable jaw firmly. It will be noticed that in all positions of the jaw plates they remain in contact with and are supported by the jaws, which is highly 70 advantageous with respect to strength and 75 rigidity.

I claim:

1. In a machine chuck, the combination with a bed plate and jaws, of jaw plates adapted to clamp the work therebetween, 75 and slideable on the jaws toward the bed plate, and pressure means engaging between the jaws and the plates to effect said sliding movement after the work is clamped, to seat and hold the work with pressure against the 80 bed plate.

2. In a machine chuck, the combination with the bed plate and jaws thereon, of jaw plates adapted to clamp the work therebetween, and slideable on the jaws toward the 85 bed plate, and screws mounted on the jaws and engaging said jaw plates to so slide the same, after the work is so clamped, to seat the work against the bed plate.

3. In a machine chuck, the combination 90 with a bed plate and jaws thereon, of jaw plates slideable on the jaws, said plates having grooves in the back thereof, and screws mounted in the jaws and having collars bearing downwardly on the jaw plates in said 95 grooves to move the plates with respect to the jaws and force the work against the bed plate.

In testimony whereof, I do affix my signature in presence of two witnesses.

OTTO EBERT.

Witnesses:
